ULTRAHIGH FREQUENCY TRANSMISSION
LINE TERMINATION

George H. Brown, Haddonfield, N. J., assignor to
Radio Corporation of America, a corporation of
Delaware

Application August 31, 1938, Serial No. 227,864

4 Claims. (Cl. 178—44)

My invention relates to terminations for transmission lines and more specifically to terminating loads for ultra high frequency power sources.

An alternating current transmission line has a characteristic impedance. If the resistance of the line per unit length is negligible, and such is the usual case, the characteristic impedance

$$Z_0 = \sqrt{\frac{L}{C}}$$

where L =the inductance per unit length and C =the capacitance per unit length of the line. If the line is terminated in a resistance equal to the characteristic impedance, reflections from the terminating impedance will be avoided. In 15 lines used for currents of a few cycles per second up to several million cycles per second, it is not a difficult problem to terminate the line in a resistance. When the frequencies extend from about thirty megacycles per second upward, as a practical matter, a pure resistance (i. e. one free from reactance is practically non-existent for power dissipation exceeding a few watts).

One of the objects of the invention is the provision of means for terminating ultra high frequency transmission lines.

Another object is to provide means for terminating an ultra high frequency transmission line such that the line termination will be a resistive load capable of substantial power dissipation.

An additional object is to provide a transmission line with a termination consisting of a second transmission line having input impedance equal to the characteristic impedance of the first line, and having a substantially resistive characteristic over a range of frequencies.

The invention will be described by reference to the accompanying drawing in which

Figure 1 is a circuit diagram of a resistively terminated transmission line;

Figure 2 is a circuit diagram of a transmission line terminated in a resistor having reactive properties;

Figure 3 is an illustration of one embodiment of the invention; and

Figures 4 and 5 are graphs used in specifically applying the invention.

In Fig. 1, a pair of conductors 1, having an input connected to a supply of alternating current, are terminated in a resistive load 3. If the lines have an inductance L and a capacitance C , their characteristic impedance

$$Z_0 = \sqrt{\frac{L}{C}}$$

If the load is chosen so that its resistance in ohms equals the characteristic impedance in ohms, undesired reflections from the terminating load will be avoided.

5 In Fig. 2 the transmission line 5 is terminated by a resistor 7 which has reactive properties represented by the dash line 9, 11 indicating respectively inductance and capacitance. If high frequency currents are applied the inductive reactance or the capacitive reactance will predominate at all but the resonant frequency. Any attempt to tune out the predominating reactance, will simply narrow the frequency range at which the termination is resistive. Furthermore, most practical applications require a resistive load over a band of frequencies and in many installations it may be necessary to dissipate considerable power.

20 Although the foregoing discussion has been applied to open conductor transmission lines, it holds equally true for concentric lines. In a concentric line of the type shown in the left portion 13 of Fig. 3 the characteristic impedance

$$Z_0 = \sqrt{\frac{L}{C}} = 60 \log \frac{b}{a}$$

where a =outside diameter of the inner conductor 15 and b =inside diameter of the outer conductor 17, provided, the resistance per unit length is negligible.

30 The problem of terminating a line carrying currents of a frequency of 30 mc. and for the dissipation of several kilowatts may be solved in accordance with my invention by terminating the first or conventional line in a second line having an input impedance equal to the characteristic impedance of the first line and having a similar frequency characteristic. If the second or terminating line has a negligible resistance per unit length, it would have to be infinitely long to have the required attenuation and propagation characteristic. To avoid this practical difficulty, a line having a conductor or conductors having the required resistance per unit length is used.

45 The characteristics of a transmission line having a highly resistive inner conductor are determined as follows:

At a reference frequency f_0 the transmission line resistance per unit length is

$$R = k(\omega_0 L) = k \frac{2\pi c L}{\gamma_0} = k \frac{2\pi}{\lambda_0} \sqrt{\frac{L}{C}} = k \frac{2\pi Z_0}{\lambda_0}$$

50 R =resistance per unit length, k =constant, $\omega_0=2\pi f_0$, c =velocity of light, λ_0 =wave length, L =inductance per unit length, C =capacitance

per unit length, and Z_0 =characteristic impedance

$$\text{or } Z_0 = \sqrt{\frac{L}{C}}$$

The true characteristic impedance:

$$Z_c = \sqrt{\frac{R+j\omega L}{j\omega C}} = \sqrt{\frac{k\omega_0 L + j\omega L}{j\omega C}} = \sqrt{\frac{L}{C}} \sqrt{1 - \frac{jk\omega_0}{\omega}}$$

$$Z_c = Z_0 \sqrt{1 - \frac{k\omega_0}{\omega}}$$

The propagation and attenuation characteristic is:

$$\alpha = \sqrt{(R+j\omega L)(j\omega C)} = \sqrt{(k\omega_0 L + j\omega L)(j\omega C)}$$

$$\alpha = \sqrt{\left(\frac{k\omega_0}{\omega} + j\right)(j\omega^2 LC)} = \frac{2\pi}{\lambda} \sqrt{j \left(\frac{k\omega_0}{\omega} + j\right)}$$

For the short circuited line it has been shown in "Communication Engineering," edition of 1932, by W. L. Everett, page 113, Equation 15, that

$$Z_{\text{input}} = Z_c \frac{\sinh \alpha h}{\cosh \alpha h} = Z_c \frac{e^{\alpha h} - e^{-\alpha h}}{e^{\alpha h} + e^{-\alpha h}}$$

where h =length of line. When $\omega = \omega_0$

$$Z_c = Z_0 \sqrt{1 - jk}$$

$$\alpha = \frac{2\pi}{\lambda} \sqrt{j(k+j)}$$

By successively setting $k=25$, 15 , and 5 (or any arbitrary values) the phase angle ϕ may be determined for a number of ratios of h/λ . These values are applied to the graph of Fig. 4, which gives the phase angle for any selection of length h to wave length λ for the chosen constant k . In a like manner graphs, Fig. 5, may be plotted for the ratio Z_{input}/Z_0 to the ratio h/λ for the several values of constant k . The application of these graphs will hereinafter appear.

Again referring to Fig. 3, the first concentric line 13 is connected to a second or terminating line 18. The second line has an inner conductor 19 which has the required resistance per unit length. The inner conductor is preferably made by coating the outer surface of a ceramic or other suitable hollow insulated form with graphite, carbon or like conductor. The terminating ends 21 may be silver or copper plated to make low resistance connections to the ground 23 and termination of the first line. The diameters of the inner and outer conductors of the second line are preferably equal respectively to those of the first line. The hollow form of the conductor 19 permits connections for cooling water, which may be used for power dissipation.

The selection of similar conductor diameters means that Z_{input}/Z_0 will equal unity. (See Fig. 5.) Therefore: for $k=25$, $h/\lambda=0.0066$; for $k=15$, $h/\lambda=0.01$ and for $k=5$, $h/\lambda=0.032$.

Now referring to Fig. 4 if the immediately foregoing h/λ values are applied to the several curves respectively, it may be seen that the phase angle ϕ is positive and fairly low and constant over a range for $k=25$, $h/\lambda=.0066$. The same is true for $k=15$, $h/\lambda=.01$. For $k=5$, $h/\lambda=.032$, the phase angle ϕ is 7.5° . It follows that $k=15$ and $h/\lambda=.01$ is an appropriate value.

By way of example, the termination for a line operating at 45 mc. and having a characteristic impedance of 70 ohms ($a=1\frac{1}{4}''$; $b=4\frac{1}{2}''$) consisted of the values indicated above. Since the total resistance should equal 70 ohms and since

$\lambda=667$ cms. and $h/\lambda=.01$, $h=6.67$ cms. Therefore the termination of a standard 70 ohm line operated at 45 mc. may be a concentric line of conductors of the same diameters and a length of 6.67 cms. with a total resistance uniformly distributed in the length h of 70 ohms. By water cooling the resistor, several kilowatts of power may be dissipated.

Thus the invention has been described as a termination for an ultra high frequency transmission line. The termination is a second line which includes a conductor having high resistance per unit length. The resistance is chosen so that the total resistance equals the impedance of the first line, and so that its phase angle of the second line is negligible. Furthermore, the resistor is arranged for water cooling in order that the power dissipation may be high. It will be observed that the grounding of the resistor makes the line especially suitable for water cooling. Instead of using the second line for terminating a standard line, it may serve other purposes. For example, the second line may be used as a load for a dummy antenna. Of course, it should be understood that the invention applies equally well to open or concentric lines.

I claim as my invention:

1. A pair of ultra high frequency transmission lines, the first of said lines having a pair of conductors having negligible resistance per unit length and a characteristic impedance

$$Z_0 = \sqrt{\frac{L}{C}}$$

where L =inductance and C =capacitance, and a second line connected to said first line, said second line including a conductor having high resistance per unit length whereby the input impedance of the second line equals the characteristic impedance of the first line and the characteristic impedance is equal to

$$Z_c = Z_0 \sqrt{1 - \frac{k\omega_0}{\omega}}$$

where k =a constant, $\omega=2\pi f$ and $\omega_0=2\pi f_0$.

2. A pair of ultra high frequency transmission lines of the character described in claim 1 including means for dissipating a substantial amount of power.

3. A pair of ultra high frequency concentric transmission lines, the first of said lines having a pair of concentric conductors having negligible resistance per unit length and a characteristic impedance

$$Z_0 = \sqrt{\frac{L}{C}}$$

where L =inductance and C =capacitance, and a second line connected to said first line, said second line including a conductor having high resistance per unit length whereby the input impedance of the second line equals the characteristic impedance of the first line and the characteristic impedance is equal to

$$Z_c = Z_0 \sqrt{1 - \frac{k\omega_0}{\omega}}$$

where k =a constant, $\omega=2\pi f$ and $\omega_0=2\pi f_0$.

4. A pair of ultra high frequency transmission lines of the character described in claim 3 including means for dissipating a substantial amount of power in said conductor of high resistance.

GEORGE H. BROWN.
